UNITED STATES PATENT OFFICE.

LOUIS M. BROWN, OF BEVERLY, MASSACHUSETTS, ASSIGNOR TO UNITED SHOE MACHINERY COMPANY, OF PATERSON, NEW JERSEY, A CORPORATION OF NEW JERSEY.

LASTING-MACHINE.

1,028,990.

Specification of Letters Patent. Patented June 11, 1912.

Application filed June 6, 1910. Serial No. 565,287.

To all whom it may concern:

Be it known that I, LOUIS M. BROWN, a citizen of the United States, residing at Beverly, in the county of Essex and State of Massachusetts, have invented certain Improvements in Lasting-Machines, of which the following description, in connection with the accompanying drawings, is a specification, like reference characters on the drawings indicating like parts in the several figures.

This invention relates to lasting machines, being herein shown as embodied in the end lasting mechanism of a machine of the "bed" type and its object is to improve wiper mechanisms of the kind used in such machines.

A particular object of the invention is to obtain a more effective bearing of the wiper upon the marginal portion of the shoe bottom for forming the upper upon the feather of the innersole and into the angle between the feather and the lip or shoulder of the innersole. It is very desirable that the upper be laid flatly down upon the feather from its edge to the shoulder to form a proper seat for the welt and it is also important that the upper be firmly pressed down into the angle, instead of bridging over the angle as it tends to do. One reason for this is found in the need for providing a seat or bearing for the binding wire with which it is customary to secure the upper in lasted position about the toe and another reason is found in the need for forming the upper down against the base of the lip or shoulder of the innersole so that it can be sewed close to said base and form a tight seam which is low enough down to allow the surplus upper stock at the inseam to be trimmed close to the face of the sole and require a minimum of filling material in the middle of the sole.

With the above-mentioned and other objects in view a feature of this invention consists in forming the end lasting wipers and their holders relatively to cause the wipers to have a local or heavy bearing upon the upper at the inner edge of that marginal portion of the shoe bottom which they overlie. This result may be obtained in numerous ways of which several are herein explained.

One novel construction embodying this in-

vention includes wiper holders provided with wiper seats that are inclined so as to pitch the wipers downwardly toward the plane of the shoe bottom and in the general direction of their advance movement. Herein the wipers, which advance and close toward each other in the well known manner, are pitched toward each other by the formation of their seats in the wiper holders. Of course the wipers might have their bodies, or the portions which are received in the seats of the holders, so formed as to give pitch to the upper engaging portions of the wipers.

One important advantage for this embodiment of the invention appears in the use of reversible wipers. Such wipers are mounted one side upward in their holders for a right shoe and the opposite side upward for a left shoe. It is customary to form wipers with a bevel to produce a thin edge. Reversible wipers of course have to be beveled on both sides. A difficulty which has been experienced heretofore has been that the bevels gave to the undersides of reversible wipers an undesirable upward pitch which caused them to bear with greatest force upon the outer edge instead of upon the inner edge of the marginal portion of the shoe bottom which they overlie. In accordance with this invention the seats in the holders for such reversible wipers are inclined to balance and preferably to overbalance the bevels at the edges of the wipers. By so doing the objectionable upward pitch is overcome and instead there may be obtained the downward pitch which is desirable for the reasons above stated.

It is of course obvious that the wipers, or the portions thereof which fit into the seats in the holders, may be given the required formation to secure downward pitch of their upper engaging portions, instead of changing the usual formation of the wiper seats in the holders. A special construction of toe wipers embodying this invention and affording certain advantages is herein shown as obtained by providing a bead or rib on the acting face of the wiper at its upper forming edge. Through the bead the pressure is emphasized or local pressure obtained at the inner edge of the marginal portion of the shoe to force the upper materials down into the angle between the

feather and the lip of the innersole and, if desired, to form a seat or crease for the toe binding wire.

Advantageously the wiper holder may be 5 undercut to present a lip 14 at the lower edge of the wiper seat and the wiper will be formed to be supported by said lip, as for example, with a counterpart groove or depression 16 in its back edge to receive said 10 lip. By the use of this formation of holder and wiper the wiper can be held in place by a single clamp with greater firmness than when the holder and wiper have simply squared abutting faces.

15 These and other features of this invention, including certain details of construction and combinations of parts, will be now particularly described and others pointed out in the claims.

20 Figure 1 is a perspective view of a toe lasting mechanism of a well known commercial form of lasting machine, the two wiper plates being separated to disclose their shape in end view. Fig. 2 is a side elevation of a wiper holder, wiper and clamp. Fig. 3 is a plan view showing one modern style of last requiring dissimilar or reversely shaped wipers for the right and left shoe. Figs. 4 and 5 show modifications. Fig. 6 25 is a detail similar to Fig. 2, but on a slightly larger scale to show clearly the undercut lip at the lower edge of the wiper seat and the coöperating groove in the wiper.

The wiper holders 2 are slidingly mounted 30 in the carriage 4 in which they are fitted between supporting and covering plates to be advanced and simultaneously closed inwardly to move the wipers 5 over the last bottom to the positions indicated in Figs. 40 2, 3, 4 and 5. This actuation is effected by connections from the wiper holders to the hand lever 6 and by the studs and cam slots shown in Fig. 3. The supporting and cover plates are carried by a lasting head 1 which 45 is vertically movable by a rod connection with a double-ended treadle, not shown, by which the wipers can be raised and depressed independently of or simultaneously with their advance and retraction by the hand lever 6. The wiper holders are cut 50 away on their under sides to form seats to receive the wipers. These seats are formed in accordance with this embodiment of this invention with upper walls that are inclined 55 to the plane in which the holders move, which plane, by suitable adjustments familiar to those acquainted with this type of machine, is made to be substantially parallel with the plane of the shoe bottom 60 which is supported by means that includes the usual toe rest 8. This inclination of the upper wall of the wiper seat in the holder will be sufficient to give to the lower acting face of the wiper a slight pitch downwardly toward the plane of the feather of

the innersole and the marginal portion of the shoe bottom upon which it is required to press in molding the shoe upper into lasted position over the feather. By this arrangement the pressure applied downwardly by the edge of the wiper is localized and the wiper is caused to crowd the upper harder down upon the innersole as it rubs over it and to apply local downward pressure adjacent to the angle between the feather and the lip or shoulder of the innersole. In Figs. 1, 2 and 3 a reversible wiper beveled on both sides is shown. In Fig. 4 a non-reversible wiper of usual construction is shown mounted in a holder having a 80 pitched wiper seat in accordance with this invention. In Fig. 5 the wiper is provided with a bead or rib 9 at its edge to apply local pressure and this construction may be used independently of the novel formation 85 of the wiper seat to give pitch to the wipers.

It is to be noted from Fig. 2 that the wiper seats in the holders extend oblique with relation to the median line of the shoe so that by the inclined walls of the seats 90 the wipers are pitched obliquely downwardly and inwardly toward the end and respective sides of the last. The rear end or wall of the wiper seat in the holder is preferably undercut, for example as shown 95 at 10 in Fig. 2, to provide a lip extending under the wiper to some degree and affording a support which aids the clamp 12 to secure the wiper rigidly in the holder and prevents any loose or tilting movement of 100 the wiper under the wiping and compressing strains to which it is subjected in operation. The reversible wiper is formed with a groove or depression as shown in said figure of the drawings to fit said lip when the 105 wiper is in the position shown in said figure or when it is reversed or turned lower side uppermost. Of course it will be understood that in reversing the wipers the plates are not only turned lower side upward but the 110 left hand plate is replaced in the right hand wiper holder as indicated in dotted lines in Fig. 3 to adapt the edge contour presented by the plates to the edge contour of the last which is mate to the one indicated in full 115 lines.

Having explained the nature of this invention and described a preferred construction embodying the same, I claim as new and desire to secure by Letters Patent of the 120 United States:—

1. In a lasting machine, shoe supporting means and end lasting mechanism including relatively movable wipers formed to embrace an end of a last, and holders therefor, 125 said wipers and holders being constructed and arranged to present the shoe engaging portion of the wipers to a shoe on said supporting means so that the wipers will normally have a localized bearing at the inner 130

edge of that marginal portion of the shoe bottom which they overlie.

2. In a lasting machine, shoe supporting means and end lasting mechanism including relatively movable wipers formed to embrace an end of a last, and holders therefor, said wipers and holders being constructed and arranged to pitch the wipers downwardly and inwardly relatively to the end 10 portion of the shoe on the support.

3. In a lasting machine, shoe supporting means and end lasting mechanism including relatively movable wipers formed to embrace an end of a last and holders for the 15 wipers having wiper seats with inclined walls formed to pitch the wipers downwardly toward the plane of the last bottom and inwardly toward the median line of the last.

20 4. In a lasting machine, shoe supporting means, and end lasting mechanism including relatively movable wipers formed to embrace an end of a last, and holders therefor, said wipers and holders being constructed 25 and arranged to adapt the wipers for operation to produce a crease to receive the binder in that surface of the overworked upper which lies parallel to the lip of the innersole.

5. In a lasting machine, shoe supporting 30 means and end lasting mechanism including relatively movable wipers formed to embrace an end of a last, holders in which the wipers are carried, and a bead formed on the lower face of the wipers at their edges.

35 6. In an end lasting mechanism, a wiper and a suitable holder therefor constructed and arranged relatively to present an edge bearing of the lower side of the wiper upon the shoe bottom adapted to produce maximum downward pressure over the angle between the feather and the lip of the inner- 40 sole.

7. In an end lasting mechanism, a wiper 45 and a suitable holder therefor constructed and arranged relatively to present to the margin of the shoe bottom a lower face of the wiper which is inclined downwardly and inwardly to bear with greatest pressure upon the upper that lies over the angle be-

tween the feather and the lip of the inner- 50 sole.

8. In an end lasting mechanism, a wiper holder which is movable between fixed guides and has a wiper seat the upper wall of which is inclined downwardly and toward its edge, and a wiper mounted by said seat in a position inclined to the path of movement of the holder whereby it is caused to bear heaviest at its edge upon the work. 55

9. In a lasting machine, wiper holders 60 having wiper seats which are inclined forwardly and downwardly toward the wiper edges substantially as and for the purpose described.

10. In a lasting machine, a wiper having 65 a bevel on each side from its front edge backwardly, and a holder having a seat for the wiper which is inclined in a direction reverse to that of the bevel on the lower face of the wiper for the purpose described. 70

11. In a lasting machine, a wiper holder and a wiper fitted thereto, said wiper being provided with a groove in its edge, and the holder with a rib to engage said groove, and additional means for securing the wiper in 75 said holder.

12. In a lasting machine, a wiper holder formed with a wiper seat that is undercut at its rear side to form a lip, and a reversible wiper having a groove or depression to receive said lip when the wiper is arranged 80 either side uppermost.

13. In a lasting machine, reversible wipers which are beveled on each side from their acting edges backwardly, and holders 85 in which the wipers are mounted at an inclination to present them to the work with their lower beveled face substantially parallel with the plane of movement of the holders. 90

In testimony whereof I have signed my name to this specification in the presence of two subscribing witnesses.
